CLAIM

The ornamental design for a tooth repair device, as shown and described.

DESCRIPTION

FIG. 1 is a front perspective view of a first embodiment of the tooth repair device;

FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof;

FIG. 8 is a bottom view thereof;

FIG. 9 is a front perspective view thereof in an alternate position; and,

FIG. 10 is a front perspective view of a second embodiment of the tooth repair device.

The broken lines show portions of the tooth repair device that form no part of the claimed design.

1 Claim, 10 Drawing Sheets(56)
